CARL GLEICHE, OF BERLIN, GERMANY, ASSIGNOR TO STOCK MOTORFLUG GESELLSCHAFT MIT BESCHRÄNKTER HAFTUNG, OF BERLIN, GERMANY, A CORPORATION OF GERMANY.

MOTOR-PLOW.

1,198,121.

Specification of Letters Patent. Patented Sept. 12, 1916.

Application filed January 20, 1915. Serial No. 3,232.

To all whom it may concern:

Be it known that I, CARL GLEICHE, a citizen of the German Empire, and resident of Berlin, Germany, have invented certain 5 new and useful Improvements in or Relating to Motor-Plows, of which the following is a specification.

My invention relates to motor-plows and has particular reference to a motor plow, 10 the frame of which is vertically adjustable relatively to one or both driving wheels about the spindle of the corresponding driving pinion or pinions.

In motor plows, the frame of which can 15 be vertically adjusted relatively to one or both driving wheels, the driving wheel is preferably mounted on a branch or arm, mounted to swing about the axis of the gear spindle supporting the driving pinion. 20 This construction has chiefly the advantage that the exact engagement of the driving pinion mounted on the gear shaft, with the teeth of the corresponding driving wheel is insured, at least when the plow, or more 25 particularly its frame, is not subjected to any twisting. Such twisting always occurs in the working of plows, and results in constant movements of the frame parts of the plow relatively to each other, more particu- 30 larly of the frame girders situated at one side, relatively to those at the other side. This twisting of the frame is so considerable that, for instance, the radiator of the engine mounted at the front end, has to be 35 protected by special means from damage liable to be caused by the twisting of the frame.

The object of my present invention is to 40 prevent, in plows of such construction, the injurious effect of movements of the plow frame or other parts of the plow, relatively to the driving parts and their connections, on the exact engagement of the driving wheels and pinions with each other. If 45 for instance, as was done hitherto, the branch or arm supporting the driving wheel, is pivoted to the frame of the plow, while the driving pinion is supported in the

gear case, in accordance with the construction usual in motor vehicles, a twisting of 50 the plow frame relatively to the casing must react more particularly on the wheels arranged on the said parts moving relatively to each other, or on the bearings of their spindles. In other words, in addition to a 55 jamming at the bearings, there will also take place a change of position between the arm pivoted to the plow frame and supporting the driving wheel, and the driving spindle or its pinion, mounted in the gear 60 case, which destroys perfect engagement of the pinion with the driving wheel. The same possibility of twisting exists even when the spindle of the driving pinion is also supported on the frame, as has already 65 been suggested. In this case also, owing to the twisting of the frame, the spindle is liable to change in the position of its support, which affects the exact engagement of the pinion mounted on the same. This is 70 obviated according to my invention by mounting the driving pinions and the branches or arms supporting the driving wheels, one inside the other (that is, concentrically), laterally on the gear case. In 75 such a case, any twisting of the plow frame can exercise a strain only on the gear case, and bring about a change of position only between the casing and the plow frame, but not between the two parts (driving wheel 80 and driving pinion) engaging with each other. Only in this way is it possible to insure completely a permanently correct engagement of the driving wheels with the driving pinions. In order to insure as far 85 as possible the connection of the driving wheel arms with the plow frame in such a method of support, the journal of each driving wheel is extended inward according to my invention and guided in a link provided on the frame. In this way, the driving wheel arm or branch as well as the driving wheel itself, is given, at any vertical position of the plow frame, a point of support against lateral movements and os- 95 cillation.

A construction according to my invention is illustrated in the accompanying drawings in which,

Figure 1 is a side elevation of a motor plow according to my invention, and Fig. 2 plan of the same. Figs. 3 to 5 are diagrammatic views of vertical movements of the frame.

The engine 1, the gear case 2 and the plow bodies 3 are all mounted on a rigid frame 4. The gear case is provided at its sides with cylindrical projections 5, 6 supported in bearings 7 and 8, secured to the frame 4. Close to the outer end, each of the projections 5, 6 is provided with a ball bearing 9 in which is supported the spindle 10 of a pinion 11 engaging with the toothed rim 12 of the corresponding driving wheel 13 or 14.

On the parts of the gear case projections 5, 6 surrounding the ball bearings 9, are pivotally mounted, concentrically or rather coaxially with the pinion 11 and its spindle 10, arms or branches 15, 16 in which are supported the axles 17, 18 of the driving wheels 13 or 14. Each of the axles 17, 18 supports an inside journal 19 guided in a link 20 or 21 secured to the frame 4 and intended to protect its arms 15 or 16 from twisting.

With the foremost end of the branch 15 engages, through a powerful helical spring 22, a cable 23 carried over three rollers 24, 25, 26 mounted on the frame 4, to a drum 27 which is supported near the driver's seat 28 and can be rotated from the said seat by means of a crank handle 30 on a spindle 29. In the same way, the cable 31 engaging with the front end of the arm 16, is carried over two rollers 32, 33 mounted on the frame 4, to a drum 34 which is arranged close below the drum 27 and can also be rotated by means of the crank handle 30 when it is applied to its spindle. The frame 4 can be moreover vertically adjusted relatively to the steering wheel 36, from the driver's seat in a well known manner by means of a crank handle 35, a positive connection 38 leading from the spindle 37 supporting the crank 35, to a pinion 39 engaging with a toothed rack 41 secured to the support 40 of the steering wheel 36.

When the plow is being driven upon a road, the frame 4 is opposite the driving wheels 13, 14 in its highest position as shown in Figs. 1 and 3. If the plow is driven on the field to be plowed, it must work, provided that the first furrow has not yet been made, with its frame 4 in the position shown in Fig. 4; and for obtaining that position the frame has to be uniformly lowered on both driving wheels 13, 14. At the beginning of the second travel of the plow, the frame is brought into the position shown in Fig. 5, by raising it again on the driving

wheel 14 which is acting as a furrow wheel, 65 by means of the drum 34 rotated by the crank 30.

While in the construction illustrated both driving wheels 13, 14 must be uniformly supported on the rigid frame in the manner 70 described, in branches or arms mounted to swing about the spindles of the driving pinions of the said driving wheels, the said method of support, in plows with a separate plow frame adjustable relatively to the main 75 frame, is necessary only for one driving wheel, for attaining the purpose in question.

Only a comparatively small effort is required for the vertical adjustment of the frame 4 relatively to the driving wheels 13, 14, as the leverage of the branches or arms 15 or 16 can be selected or proportioned in a very favorable manner for the purpose. It is also important that the arms 15, 16 are supported in a reliable and firm manner 85 on the parts of the outward projections 5, 6 of the gear case 2, surrounding the bearings 9 of the driving pinions 11. It is further very important for the whole construction of the plow that lateral arms of the gear 90 case 2, viz., the above mentioned projections 5, 6 are used as bearings for the branches or arms. This arrangement, in addition to the advantages mentioned in the beginning, has also the further advantage that the gear case 95 itself forms a transverse girder for the frame 4, and that the three-point-suspension which is desirable in all motor vehicles, is insured in any position, even during the adjustment of the frame 4 or twisting of 100 the frame.

I claim:

1. In a motor-plow, a frame carrying the driving pinion for the driving wheel of the plow, an arm supporting said driving wheel 105 and capable of being swung about the axis of said driving pinion, the bearings of said pinion and of said arm being arranged one inside the other on a lateral projection of the gear case of the plow. 110

2. In a motor-plow, a frame carrying the driving pinion for the driving wheel of the plow, an arm supporting said driving wheel and capable of being swung about the axis of said driving pinion, a link, mounted on 115 the frame and guiding said arm against twisting.

3. In a motor-plow, a frame carrying the driving pinion for the driving wheel of the plow, an arm supporting said driving wheel 120 and capable of being swung about the axis of said driving pinion, the bearings of said pinion and of said arm being arranged one inside the other on a lateral projection of the gear case of the plow, a link, mounted 125 on the frame and guiding said arm against twisting.

4. In a motor-plow, a frame carrying the

driving pinion for the driving wheel of the plow, an arm supporting said driving wheel and capable of being swung about the axis of said driving pinion, and a link carried by the frame and curved concentrically with said axis, said link being in bracing relation to said arm to protect it against twisting.

In testimony whereof, I have signed this specification in the presence of two subscribing witnesses. 10

CARL GLEICHE.
